CLAIM

The ornamental design for a urinal receptacle, as shown and described.

DESCRIPTION

Fig. 1.1 is a top plan view of my new design for a urinal receptacle in an unfolded state, the remaining figures illustrating the new design in a folded state;

Fig. 1.2 is a right side perspective view thereof;

Fig. 1.3 is a top, left, front perspective view thereof;

Fig. 1.4 is a right side elevation view thereof;

Fig. 1.5 is a front elevation view thereof;

Fig. 1.6 is a rear elevation view thereof; and

Fig. 1.7 is a top plan elevation view thereof.

The broken lines in the drawings illustrate portions of the urinal receptacle and form no part of the claimed design.

1 Claim, 7 Drawing Sheets
